UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

PERCUSSIVE TOOL.

Application filed June 30, 1916. Serial No. 106,960.

To all whom it may concern:

Be it known that I, HENRY H. MERCER, a citizen of the United States, residing at Claremont, in the county of Sullivan, and 5 State of New Hampshire, have invented certain new and useful Improvements in Percussive Tools, of which the following is a full, clear, and exact specification.

My invention relates to percussive tools.

10 It has for its object to provide an improved tool especially adapted to use in channelers whereby a straight cut or channel may be produced and any tendency of the tool to run in under or side-ways as the 15 cut is lengthened is effectually counteracted, thereby eliminating crooked cuts and the various resultant delays in the operation of the machines. A further object of the invention is to provide an improved tool for 20 cutting and breaking off rock portions in an improved manner such as is disclosed and claimed in my co-pending application, Number 106,961, filed June 30, 1916. In this improved manner of making cuts in a rock 25 formation, advantage is taken of the fact that when a thin portion of rock is cut off or when a relatively narrow cut is made by a plurality of cutting instruments operating on opposite sides of the cut, the narrow portion 30 of rock cannot withstand the hard blows of the cutting tools and will crumble or break under the force of the blows, especially when a part of the force of the blow is directed toward the portion to be cut off. 35 These and other objects of my improved construction will hereinafter appear.

In the accompanying drawings, I have, for purposes of illustration, shown two embodiments which my invention may assume 40 in practice.

In these drawings.—

Fig. 1 is a transverse sectional view of a channel, showing one form of my improved tool in side elevation therein.

45 Fig. 2 is a perspective view of the cutting end of the tool.

Fig. 3 is a perspective view of the cutting end of a tool of the same type shown in Fig. 2, the tool being shown in reversed position and of slightly modified construction.

50 Fig. 4 is a perspective view of the cutting end of a further modified form of tool.

Fig. 5 is a similar view showing a tool of the type shown in Fig. 4, the tool being

shown in reversed positions and of slightly 55 modified construction.

In the form of my invention illustrated, I have shown tools of the gang type which may, if desired, be formed of one piece or of a plurality of cooperating steels joined in 60 a well known manner.

As shown in Fig. 1, it will be noted that the tool is provided at its end with a cutting edge 1 extending transversely thereof and inclined downwardly with respect to the 65 length of the tool toward the wall of the channel adjacent the channeler. It will also be noted that the latter is provided on its back with an elongated flat back 2 adapted to bear against the wall of the channel adjacent the channeler in vertical cutting and that the same is also preferably provided with a shorter flat face 3 adapted to bear against the opposite wall of the channel. Thus, due to the inclined cutting edge 1, 70 which forms an acute angle with the back 2 in a plane or surface disposed longitudinally of the tool, the normal tendency of the tool, as it is sunk into the rock, is to work in under the wall adjacent the channeler while the tendency of the back 2 is to correct or neutralize this running in action of the tool to such an extent that, as the tool 75 is sunk, it must move in a straight path. It will of course be understood that the face 3 80 may also cooperate with the back 2 in bringing about this result, although this is not 85 essential.

As illustrated in Fig. 2, I preferably employ a tool of the Z gang type having at its 90 end a plurality of inclined spaced chisel or cutting edges 1 disposed transversely of the cut and constituting what may be called 95 chopping edges. As shown, these edges are connected by a cooperating angular web 95 preferably comprising two leveling edges 4 and 5, of which the former is preferably shorter than the edges 1 and is disposed inside one of the edges 1 and extends at right angles thereto, while the latter connects the edge 4 to the other edge 1, and is disposed at an angle of substantially 45° to the other edges in a plane or surface transverse to the tool. In this construction, it will be noted 100 that the back of the tool is provided with a plurality of flat surfaces 2 spaced apart on opposite sides of the tool, which, due to their large area and their spaced location 105

with respect to one another, obviously act efficiently to prevent the running in under of the tool. It will also be noted that, as shown in Figs. 2 and 3, a plurality of spaced 5 surfaces 3 is provided and that the edges 4 and 5 are provided with inclined surfaces 6 and 7 sloping toward the same in such a manner as to facilitate the reduction of the stone. The tool shown in Fig. 3 obviously 10 differs from that shown in Fig. 2, only in that it comprises a plurality of cutting members or steels united to form one tool or gang.

In the form of my invention shown in Fig. 15 4, it will be noted that the tool is provided with central leveling edges 8 and 9 disposed in V shape between a plurality of edges 10 and 11 similar to the leveling edge 4 above described, and that the edges 10 and 11 20 are located adjacent the cutting edges 1, as in the construction first described. In the tool shown in Figs. 4 and 5, it will also be noted that the edges 8 and 9 are formed on inclined portions 12 and 13 leading to 25 the level of a plurality of surfaces 2, similar to the surfaces above described, and that an intermediate surface 3 is provided disposed in the same plane with the other surfaces 3, and cooperating therewith. The gang 30 shown in Fig. 5 is of the same shape as that shown in Fig. 4, and only differs therefrom in being formed of a plurality of steels. In the drawings I have shown the cutting edges and the leveling edges in substantially the 35 same plane, but it will be obvious that, as usual in the channel art, the relative position of cutting and leveling edges will be dependent upon the hardness and other characteristics of the matter being channeled. In some 40 cases the leveling edges may be retracted even more than as shown in Fig. 2, i. e., as much as one-fourth of an inch, or even more, above the level of the cutting edges.

In the use of my improved construction, 45 due to the tendency of the inclined cutting edges 1 to cause the tool to run in under the wall of the cut adjacent the channeler, and the constant counteracting effect of the flattened backs or surfaces 2, a channel is 50 produced which is substantially straight, thereby removing a large part of the difficulties heretofore experienced with the tools or gangs, and the necessity for straightening the cut as the latter is lengthened. A part 55 of the force of the blow delivered by the cutting tool is absorbed in cutting into the rock and, due to the use of a slanting cutting edge, one component of this force is directed toward the rock portion to be cut away, to 60 break this rock portion, as shown at X and Y, free from the uncut rock formation.

While I have in this application specifically described two embodiments which my invention may assume in practice, it is to be 65 understood that the same is not limited there-

to but may be embodied in various other forms without departing from its spirit, it being my intention to include all such modifications within the scope of the appended claims.

What I claim as new and desire to secure by Letters Patent is:

1. A channeler steel for cutting a portion of rock free from a rock formation comprising a shank, and a cutting tool at the lower end of said shank, said tool being provided with a cutting portion terminating in a chisel-like chopping edge, extending substantially across the entire lower end of said tool, said edge being substantially straight and making a small angle with a plane to which the direction of reciprocation of said steel when in use is perpendicular, whereby the main action of said edge is a cutting one but a small component of the blow transmitted by said edge is directed in the direction of the rock portion to be freed, and said tool being also provided with a guiding surface disposed parallel to its direction of reciprocation and formed at the side thereof in which the lower end of said cutting edge terminates.

2. A channeler steel for cutting a portion of rock free from a rock formation comprising a shank, and a cutting tool at the lower end of said shank, said tool being provided with a plurality of parallel transverse chisel-like chopping edges extending substantially across the entire lower end of said tool, said edges being substantially straight and making a small angle with a plane to which the direction of reciprocation of said steel when in use is perpendicular, whereby the main action of said edges is a cutting one but a small component of the blow transmitted by said edges is directed in the direction of the rock portion to be freed, and said tool being also provided with a guiding surface disposed parallel to its direction of reciprocation and formed at the side thereof in which the lower ends of said cutting edges terminate.

3. A channeler steel adapted during cutting operation for reciprocation and simultaneous gradual bodily lateral movement in a plane including the axis of the steel, comprising a shank, a guiding surface parallel to the direction of bodily lateral movement, and a cutting edge extending from said guiding surface and making a small angle with a plane perpendicular to the length of the shank, said cutting edge running completely across the end of the shank and being disposed also in a vertical plane substantially perpendicular to said guiding surface, whereby a small component of the blow delivered by the cutting edge is directed away from said guiding surface to effect the breaking off of a rock portion cut free by said steel.

4. In a percussive tool for cutting a portion of rock free from a rock formation, a guiding means, a transverse downwardly directed cutting edge and a diagonal cutting edge both disposed substantially in a plane which extends across the end of the tool and makes a small dihedral angle with a plane to which the length of said tool is perpendicular.
5. In a percussive tool for cutting a portion of rock free from a rock formation, a guiding surface on said tool adjacent the rock formation, a transverse downwardly directed cutting chopping edge and a diagonal cutting leveling edge disposed substantially in a plane extending across the end of the tool and making a small dihedral angle with a plane to which the length of said tool is perpendicular.
6. In a percussive tool for cutting a portion of rock free from a rock formation, a guiding surface on said tool contacting with the rock formation and cooperating therewith to guide the tool, and a bit provided with a plurality of transverse downwardly directed chopping edges and with a diagonal cutting edge and having its transverse edges disposed in a plane extending across the end of the bit and making an acute dihedral angle with the guide surface to deliver a component of the force of the blow in the direction of the rock portion, the complement of said dihedral angle being materially smaller than said angle itself.
7. In a percussive tool for cutting a portion of rock free from a rock formation, a guiding surface on said tool contacting with the rock formation and cooperating therewith to guide the tool, and a bit comprising a transverse downwardly directed chopping cutting edge and a diagonal leveling cutting edge and having its transverse and diagonal cutting edges disposed in a plane extending across the end of the bit and making an acute dihedral angle with the guiding surface to deliver a component of the force of the blow in the direction of the rock portion, said dihedral angle being of such measure that its complement is materially smaller than said angle itself.
8. In a percussive tool for cutting a portion of rock free from a rock formation, a guiding surface on said tool contacting with the rock formation and cooperating therewith to guide the tool, and a bit including a plurality of transverse downwardly directed chopping cutting edges and an angular diagonal cutting edge therebetween, said transverse cutting edges being disposed in a plane which extends across the end of the bit and makes an acute dihedral angle with the guiding surface to deliver a component of the force of the blow in the direction of the rock portion, said dihedral angle being of such measure that its complement is materially smaller than said angle itself.
9. In a percussive tool for cutting a portion of rock free from a rock formation, a guiding surface on said tool contacting with the rock formation and cooperating therewith to guide the tool, and a bit including a plurality of transverse downwardly directed chopping cutting edges and an angular diagonal cutting edge therebetween, said cutting edges being disposed in a plane extending across the end of the bit at an acute angle to the guiding surface to deliver a small component of the force of the blow in the direction of the rock portion.
10. In a percussive tool for cutting a portion of rock free from a rock formation, a guiding surface on said tool contacting with the rock formation and cooperating therewith to guide the tool, and a bit including a plurality of transverse cutting edges and an angular cutting edge comprising a plurality of cutting edges one of which is parallel to said guiding surface and disposed between the transverse cutting edges, a part of said cutting edges being disposed in a plane extending across the end of the bit at a relatively large acute angle to the guiding surface and intersecting the latter along a line perpendicular to the length of the tool to deliver a component of the force of the blow in the direction of the rock portion.
11. A percussive tool for channelers having an elongated straight back adapted to engage one wall of a cut and having at its end a plurality of spaced inclined chopping edges extending transversely of the tool and making small acute angles with a plane to which said back is perpendicular and lying in surfaces disposed longitudinally of the tool.
12. A percussive tool for channelers having an elongated straight back adapted to engage one wall of a cut and having at its end a plurality of spaced chopping cutting edges extending transversely of the tool and inclined with respect to said back in surfaces disposed longitudinally of the tool, and a cooperating cutting edge disposed between said first named cutting edges and having the extremities thereof the one adjacent the back of the tool and the other adjacent the front side thereof, the foremost point in the first mentioned cutting edges being at least as far forward as the foremost point in said cooperating edge.
13. A percussive tool for channelers having an elongated straight back adapted to engage one wall of a cut and having at its end a plurality of spaced cutting edges extending transversely of the tool and inclined with respect to said back in surfaces disposed longitudinally of the tool, and a plurality of cutting edges between said first

named cutting edges, said last named cutting edges being angularly disposed with respect to each other in a surface which is transverse to the tool and makes a small 5 dihedral angle with a surface to which the tool is perpendicular, there being a point in one of said cooperating edges adjacent the back of said tool and a point in the other thereof adjacent the front side of said tool, 10 the foremost points in said plurality of spaced cutting edges being at least as far advanced as the foremost points in said cooperating edges.

14. A percussive tool having a straight 15 back adapted to engage the wall of a cut, and having at its end a cutting portion comprising downwardly directed chopping edge portions extending transversely of the tool and forming acute angles with said back in 20 surfaces disposed longitudinally of the tool, and an edge joining the diagonally opposite extremities of said edge portions.

15. A percussive tool having at its end a plurality of spaced chopping cutting edges 25 extending transversely of the tool and inclined with respect to the length thereof, and cooperating leveling edges between said transversely extending edges and angularly disposed with respect thereto in a surface 30 transverse to the tool.

16. A percussive tool having at its end a plurality of spaced chopping cutting edges extending transversely of the tool and inclined with respect to the length 35 thereof, and cooperating leveling edges between said transversely extending edges and angularly disposed with respect thereto in a surface transverse to the tool, said tool having a plurality of elongated flat 40 surfaces on its back.

17. A percussive tool having an elongated straight back adapted to engage one wall of the cut, and having at its end a plurality of spaced inclined cutting edges extending 45 transversely of the tool and forming acute angles with said back in surfaces disposed longitudinally of the tool, a cooperating shorter leveling edge disposed adjacent one

of said transversely extending edges, and a second cooperating leveling edge disposed angularly with respect to said first named cooperating edge in a surface transverse to the tool and disposed between said first named cooperating edge and the other of said transversely extending edges. 50 55

18. A percussive tool comprising a pair of parallel downwardly directed chopping cutting edges and an intermediate leveling edge, said edges being disposed substantially in a single plane which passes through a line 60 perpendicular to the axis of the tool and to which plane said axis is oblique.

19. In a percussive tool, a pair of downwardly directed chopping cutting edges disposed adjacent the sides of the tool and lying in a plane which passes through a line 65 perpendicular to one of the sides of said tool and makes a relatively large acute dihedral angle with the plane of the back of the tool, and a leveling edge disposed in substantially the same plane but arranged at an angle to said cutting edges. 70

20. In a percussive tool for channelers, a guiding surface on the tool contacting with the rock and cooperating therewith to guide 75 the tool, a leading cutting edge lying in a plane transverse to the direction of advance of said tool, a second cutting edge parallel to the said first edge, and an intermediate leveling edge arranged at an angle to said cutting edges, all of said edges being disposed substantially in a single plane which passes through a line connecting homologous points in the cutting edges 80 and makes a relatively large acute dihedral angle with the guiding surface. 85

21. A channeler tool gang comprising a plurality of transverse chopping cutting edges disposed in a plane making a relatively large acute angle with the walls of the channel which is cut thereby, and an intermediate leveling edge arranged in a plane parallel to a plane parallel to said first mentioned plane. 90

In testimony whereof I affix my signature.
HENRY H. MERCER.
